UNITED STATES PATENT OFFICE.

JEAN F. WEBB, JR., OF NEW YORK, N. Y., ASSIGNOR TO THE ELECTRIC SIGNAGRAH
AND SEMAPHORE COMPANY, INCORPORATED, OF NEW YORK, N. Y.

CONTACT-MAKER.

1,030,441.

Specification of Letters Patent. Patented June 25, 1912.

Original application filed January 27, 1910, Serial No. 540,394. Divided and this application filed May 17, 1911. Serial No. 627,702.

To all whom it may concern:

Be it known that I, JEAN F. WEBB, Jr., residing at New York, in the county of New York and State of New York, have invented 5 certain new and useful Improvements in Contact-Makers, of which the following is a specification.

The invention is a contact maker especially designed for electric signaling and 10 train control use, and it particularly has for its object to provide a contact maker by means of which good electrical connection between the train carried mechanism and the conductor rail may be had.

15 This application is a divisional part of my copending application, filed January 27, 1910, Serial #540394.

The invention also resides in those novel 20 details of construction, combination and arrangement of parts, all of which will be first fully described and then be specifically pointed out in the appended claims, reference being had to the accompanying drawing, in which:

25 Figure 1 is a side elevation of the contact maker. Fig. 2 is a vertical longitudinal section on the line 2—2 of Fig. 1. Fig. 3 is a detail section on the line 3—3 of Fig. 2.

Referring now to the drawing, in which 30 like numerals and letters of reference indicate like parts in all of the figures, the contact maker 17 comprises two angle irons 17^a—17^a riveted together at 17^b and secured by rivets 17^c to the cross channel bar 1^d of 35 the wheeled truck, insulation 17^e—17^f being provided to electrically insulate the contact maker from the trucks. The angle irons 17^a—17^a each have a pair of vertically disposed slots 17^g for the bearings 17^h that 40 carry the shafts 17ⁱ which are bolted at 17^j to the bearings to hold the same from turning. Ball bearings 17^k connect the shaft 17ⁱ and contact wheels 17^l. Pins 17^m, on angle irons 17ⁿ, hold springs 17° to press down on 45 the bearings 17^h. The angle irons 17ⁿ are riveted at 17^p to the depending part of the angle irons 17^a, the rivets also passing through a spacing and bracing block 17^q. Contact fingers 17^r on the blocks 17^q engage 50 the wheels 17^l to insure good electrical con-

tact, although such contact fingers may be omitted, if desired, as the wheels 17^l are always in electrical connection with the block 17^q and framing 17^a, through the axles 17ⁱ, bearings 17^h, and springs 17°, etc. The 55 wheels 17^l may have lubricant holding chambers 17^s into which a lubricant may be introduced through a bore 17^t that is normally closed by a plug 17^u.

The operation of the invention will be 60 readily apparent by an inspection of the drawing, in which 21 designates the contact rail on which the contact maker runs to complete the electrical continuity between the rail 21 and the brushes and contact fingers 65 17^r.

From the foregoing description taken in connection with the accompanying drawing, it is believed the complete construction, operation and advantages of the invention will 70 be apparent to those skilled in the art.

What I claim is:—

1. A contact maker comprising a pair of angle irons secured together, and having depending parts spaced apart, said depending parts having bearing slots, bearing boxes, a shaft passing through said depending parts and secured from rotation in said bearing boxes, angle irons secured to said depending parts, spring holding lugs carried by said angle irons, springs on said lugs to engage said bearing boxes to tend to move said bearings in one direction, and a contact wheel rotatable on said shaft, all being arranged substantially as shown and described. 75

2. A contact maker comprising a pair of angle irons, secured together and having depending parts spaced apart, said depending parts having vertical slots, bearings mounted in said vertical slots, a shaft mounted in said bearings, means continuously tending to hold said bearings in one position, a contact wheel rotatable on said shaft, and means insuring good electrical connection 90 between said wheel and said angle irons. 95
